UNITED STATES PATENT OFFICE.

CHARLES DICKSON, OF NEW YORK, N. Y.

CIGAR-LIGHTER. BEST AVAILABLE COPY

1,006,447.

Specification of Letters Patent. Patented Oct. 17, 1911.

Application filed December 17, 1910. Serial No. 597,745.

To all whom it may concern:

Be it known that I, CHARLES DICKSON, a citizen of the United States, and a resident of the borough of Manhattan of the city of New York, in the county and State of New York, have invented certain new and useful Improvements in Cigar-Lighters, of which the following is a specification, reference being had to the accompanying drawings, forming a part hereof.

10 The invention relates to improvements in automatic pocket lighters for cigars, cigarettes, etc., wherein a knife-edge is arranged to be drawn or scraped across a suitable 15 pyrophoric substance to produce the ignition of a wick lying in the path of the sparks which are thereby made to emanate therefrom.

15 The object of the present improvements is three-fold: first, to insure a sufficient and uniform scraping of the pyrophoric substance by the knife edge to produce to a certainty the ignition of the wick each time the device is operated; second, to improve 25 these devices with particular reference to convenience of operation and use; and third, to simplify their construction and reduce the cost of manufacture.

More particularly will the invention be 30 described in connection with the accompanying drawings, in which,

Figure 1 is a view of one of the improved devices in side elevation. Fig. 2 is a view in longitudinal section. Fig. 3 is a view in 35 end elevation. Fig. 4 is a view in transverse section, the plane of section being indicated by the line 4-4 in Fig. 2. Figs. 5 and 6 are detail views, in section and side elevation respectively, of a plug employed in the 40 device, the plane of section of Fig. 5 being indicated by the line 5-5 in Fig. 6. Fig. 7 is a detail view of the plug and cap showing a modification.

The general shape of the improved lighter 45 is that of a flat pocket match box with the corners at the bottom preferably rounded as shown. There are only three parts required in making up the device: the reservoir *a* which forms the bottom and which 50 contains the gasoline or other liquid used; a plug *b* which has a close sliding fit with the top of the reservoir and in which there is an opening *c* at one end for the wick *d*; and finally, a sliding cap or cover *e* which 55 is adapted to move longitudinally across the plug.

The plug will be seen to be long and narrow, and the cover, sliding as it does across the plug in the direction of its length, provides an ample opportunity for a long uniform contact between the pyrophoric substance and the scraper or knife edge. The latter is arranged on the plug where it is designated by *f* and the pyrophoric substance is arranged in a strip *g* along the 60 underside of the top of the cover. A suitable pyrophoric substance for use in this connection is the well known composition of iron and cerium.

It will be understood that the positions 70 of the pyrophoric substance and scraper may be interchanged; in fact the modification of Fig. 7 shows the pyrophoric substance mounted in a container *g* upon the plug, the scraper consisting of a corrugated 75 surface *f* formed on or secured to the underside of the cap. In either case, all one has to do is to slide the cover the length of the plug or less while it is automatically guided by the sides and shoulder *h* of the 80 plug, and the ignition of the wick cannot fail to take place. Nothing is left to the fancy, or will, of the user. Moreover, the shoulder *h* on one side of the plug is reduced to a small section *i* which acts as a stop 85 (Fig. 5) and prevents the cover from being slid clear off the plug.

The upper part of the plug is made hollow, the side-walls thus formed providing 90 suitable means for the cover to slide on, and the hollow making a very convenient place for the wick, for it is there protected from being extinguished by drafts while at the same time it may draw plenty of air. The 95 whole device is free of screw-threads, hinges and the like whereby it may be manufactured with very little machining or handling, and the assembling of the three parts is obviously of the simplest. Finally, the personal equation of the user is entirely 100 eliminated in the operation of the device, thus making the latter automatic and certain.

I claim as my invention:

1. In a cigar lighter, the combination of 105 a reservoir, a plug having a tight sliding fit therein and containing a hole for a wick, a cover fitting on said plug and adapted to slide longitudinally across the same, a scraper, and a pyrophoric substance arranged so as to be scraped by the scraper as the cover is slid across the plug.

2. In a cigar lighter, the combination of a reservoir, a plug having a tight sliding fit therein and containing a hole for a wick, a cover fitting on said plug and adapted to slide longitudinally across the same, a pyrophoric substance carried by the cover, and a knife-edge upon the plug which is adapted to scrape the pyrophoric substance as the cover is moved across the plug.
- 10 3. In a cigar lighter, the combination of a flat reservoir, a long narrow plug having a tight sliding fit therein and containing a hole for a wick near one end, a cover fitting over said plug and adapted to slide longitudinally across the same in the direction of its length and away from the wick, a knife-edge projecting upwardly from the plug near the wick hole, and a pyrophoric substance on the inner side of the cover and adapted to be scraped by the knife-edge as the cover is slid across the plug.
- 15 4. In a cigar lighter, the combination of a reservoir, a plug having a tight sliding fit therein and formed with a hollow in its top and a wick-hole extending down through the plug from the hollow, a cover embracing the sides of the plug around the hollow and adapted to slide longitudinally across the plug, a scraper, a pyrophoric substance arranged so as to be scraped by the scraper as the cover is moved, and means to prevent the cover becoming detached from the plug.

This specification signed and witnessed this 9th day of December, A. D., 1910.

CHARLES DICKSON.
